(57) **CLAIM**

I claim the ornamental design for shoe upper, as shown and described above.

DESCRIPTION

FIG. 1 is a top, front and left side perspective view;

FIG. 2 is a top plan view thereof;

FIG. 3 is a front elevational view thereof;

FIG. 4 is a rear elevational view thereof;

FIG. 5 is a left side elevational view thereof; and,

FIG. 6 is a right side elevational view thereof.

The designation ECCO and markings visible on the insoles form no part of the claimed design.
